UNITED STATES PATENT OFFICE.

EARL E. STEELE, OF TOLEDO, OHIO.

ROPE-FASTENER.

1,205,808.

Specification of Letters Patent. Patented Nov. 21, 1916.

Application filed February 16, 1916. Serial No. 78,631.

To all whom it may concern:

Be it known that I, EARL E. STEELE, a citizen of the United States, residing at Toledo, in the county of Lucas and State of Ohio, have invented certain new and useful 5 Improvements in Rope-Fasteners, of which the following is a specification.

This invention relates to improvements in rope fasteners, that is to a metal device that 10 will coöperate with the terminal of a rope and provide a fixed abutment in lieu of a knot from the body of the rope, as is the usual practice, one object of the invention being the provision of a strip of malleable 15 metal provided with openings for the reception of the rope which is coiled coextensively therewith, so that the metal strip is firmly attached to the rope.

A further object of the present device is 20 the provision of means for forming a permanent knot at the end of a rope, such as a sash cord and clothes line, the strip when used with the latter being provided with a free attaching end, whereby the same may 25 engage a hook or other supporting connection, and thus render it unnecessary to tie the rope in a number of knots.

In the accompanying drawings: Figure 1 is a plan view of a rope fastener embodying 30 the present invention. Fig. 2 is a side elevation thereof in coiled formation. Fig. 3 is a view of the same applied to a sash cord. Fig. 4 is a similar view as applied to a clothes line and supporting hook.

35 Referring to the drawings, the numeral 10 designates a metal strip, which is malleable and readily coiled to present the partial coil 11, having the embraced substantially diametrical terminal 12, and the long terminal 13. Formed through the body of the strip 40 are preferably the three apertures 14 and 15, the two apertures 14, being circular, while the aperture 15 is provided with the V-shaped portion 16, longitudinally of the strip and extending toward the terminal 12, intermediate the strip 10 being bent at 17, intermediate 45 of the elongated opening 15.

In using the present fastener upon a sash cord 18, the extreme end of the cord is 50 passed through the opening 14 nearest the opening 15, and then extended through the opening 15, to assume the position as shown in Fig. 3, the metal strip being cut off at 19.

By pulling upon the sash cord the hooked end portion thereof at its point of engagement with the angular portion 17 of the metal knot will be wedged in the portion 16 of the opening 15, and thus securely lock the fastener upon the cord.

When the device is used upon a clothes 60 line, the terminal 20 thereof is inserted in the same manner, but the long terminal of the device with the other opening 14 is retained, so that the opening 14 may be passed over the supporting hook 21, as shown clearly 65 in Fig. 4.

What I claim as new is:—

1. A fastener for a rope comprising a strip of relatively stiff material bent at one end portion thereof to provide a partial coil and 70 a straight terminal extended within the coil parallel with the remaining portion of said strip, said strip being provided with apertures, one of which is located at the bight between the coil and said straight portion 75 and having a wedge portion while the other aperture is located in the coil at one side of the plane of said portion.

2. A fastener for rope, made from a strip of metal and provided with a plurality of 80 apertures, one of which is provided with a wedging portion, said strip being bent to form a partial coil having one straight terminal embraced by the coil, the aperture with the wedging portion being at the junction 85 of the coil and the straight terminal.

3. A fastener for rope, made from a strip of metal and provided with a plurality of apertures, one of which is provided with a wedging portion, said strip being bent to 90 form a partial coil having one straight terminal embraced by the coil, the aperture with the wedging portion being at the junction of the coil and the straight terminal, the other terminal of the strip being extended in an opposite direction to the embraced terminal and having an aperture to receive a supporting hook, the intermediate 95 and wedging apertures forming receptacles for the rope.

4. A rope fastener comprising a member 100 formed with a coil and a straight portion formed with an open coil and a straight portion extended within said coil and forming a bight at the juncture of said portion 105 with the coil, said coil having a plurality of

apertures, one of the apertures being wedge-shaped and located to intersect the bight between the straight portion and the coil.

5. A rope fastener comprising a strip-like body bent to form reversely extending straight portions and an open coil, one of said straight portions being encircled by the

coil, said coil being apertured at spaced points thereof, one of the apertures being of wedge shape and extending into the last named straight portion.

In testimony whereof I affix my signature.

EARL E. STEELE.
